UNITED STATES PATENT OFFICE.

WILLIAM ESTY, OF LACONIA, NEW HAMPSHIRE, ASSIGNOR OF TWO-THIRDS
TO LEWIS F. BUSIEL, OF SAME PLACE, AND GEORGE W. SHERWELL, OF
LAKE VILLAGE, NEW HAMPSHIRE.

STEAM-ENGINE.

SPECIFICATION forming part of Letters Patent No. 367,029, dated July 26, 1887.

Application filed April 14, 1887. Serial No. 234,802. (No model.)

To all whom it may concern:

Be it known that I, WILLIAM ESTY, of Laconia, in the county of Belknap and State of New Hampshire, have invented a new and 5 useful Improvement in Steam-Engines, of which the following, taken in connection with the accompanying drawings, is a specification.

My present invention is an improvement upon the engine described in Letters Patent 10 No. 355,814, granted to me January 11, 1887, and has for its object the production of a more effective and reliable thrust-bearing for the shaft, which I have found to be very desirable when the engine-shaft is used as a screw-propeller shaft; and it consists in certain novel 15 features of construction, arrangement, and combination of parts relating particularly to the crank end of the engine, all of which will be readily understood by reference to the description of the drawings and to the claims to 20 be hereinafter given.

Figure 1 of the drawings is a central vertical longitudinal section of my improved engine. Fig. 2 is a partial elevation of the valve, 25 and Fig. 3 is a transverse section through one side of the valve and the compression-ring enlarged.

In the drawings, A is the cylinder-casting, having formed therein a series of cylinders, as 30 a a', &c., preferably six in number, arranged in a circle concentric with the axis of the shaft B and with their axes parallel to the axis of said shaft, substantially as described in the Letters Patent before cited.

35 The valve-seat C and all of the parts shown in Fig. 1 of the drawings to the left thereof except the valve are constructed, arranged, and operate substantially as described in said prior patent, and therefore will need no further 40 description here.

The cylinder-casting A is made somewhat longer than the same part was made in said prior patent, and has the end h' of its central hub and all that portion of said casting inside 45 of the annular exhaust-chamber b made conical, the angle of said conical surface being a right angle to an imaginary cone described by

the axis of the oblique portion B' of the shaft when said shaft is revolved.

The pistons D D are hollow cylinders having both ends closed, one end being cast in and the other being closed by a screw-plug having formed thereon a ball, c, to which is fitted the socketed shoe d, the flat side of which rests against the annular flat surface e of the 55 hemispherical crank-sleeve E.

An annular casting, F, is bolted to the end of the cylinder-casting A opposite to the valve-seat C, and has formed therein a portion of a hemispherical chamber, F', and a short cylindrical opening, F'', through its center, which is closed or covered by the cup-like casting G, bolted to the casting F, and having set in its center the stud H, having at its inner end a concave head made to fit the spherical surface 65 of the crank-sleeve E and adapted to receive the endwise thrust of the shaft B.

I is the counterweight-lever mounted upon the stud H, about which it is revolved when the shaft B is revolved by the action of the 70 crank-pin f, which enters a hole formed in the light arm of said lever, as shown.

The crank-sleeve E, instead of being made with radial arms and connected to the pistons by connecting rods and ball-and-socket joints, 75 as in my prior patent, is a hollow casting in the form of a hemisphere pierced with a hole at right angles to the flat or equatorial plane of said hemisphere, said hole being fitted with a composition bushing, g, to fit the oblique 80 portion B' of the shaft B, as shown.

The outer wall of the casting A is disconnected from the walls of the cylinders a a', &c., at the end next the casting F, so that the annular exhaust-chamber b communicates with 85 the hemispherical chamber F', and through it with the space inside the circle of cylinders, and thence through the spaces between the ring-valve and its hub to the chamber surrounding the reversing-gear and the stern-bearing J, said exhaust-steam finally escaping 90 from the engine through the pipe K. By this construction and arrangement of parts I have produced a very efficient and durable thrust-

bearing without increasing the cost of the engine.

In the operation of the engine the flat side of the hemispherical crank-sleeve, as the shaft is revolved, rolls about the conical surface *h*, while the convex surface thereof rolls in the hemispherical concave formed in the casting *F* and the end of the head of the stud *H*, as shown. As the pistons *D D* are not connected to the hemispherical sleeve, if the steam should be completely exhausted from the cylinders their pistons would be liable to pound or hammer the heads of the cylinders as they were moved inward after the steam was exhausted; but the exhaust-ports are so constructed relative to the strokes of the pistons that some steam remains in each cylinder when its exhaust-port is closed by the inward movement of its piston, and, instead of allowing such remaining steam to escape freely into the annular chamber of the ring or disk valve, as in my before-mentioned prior patent, I throttle the escape of this remaining steam through steam-port by means of the adjustable annular compression-ring *m*, provided with a male screw-thread on its inner periphery, which fits a corresponding female thread in the outer wall of the annular rectangular groove *n*, formed in the face of the valve *J*, as shown. In the bottom of the groove *n* is formed a series of holes, *o*, to receive the end of the locking-pin *p*, which is screwed into the ring *m* and enters one of said holes to lock the ring against accidental displacement when once properly set. By setting this ring *m* so that it will almost touch the valve seat, the remnant of steam left in the cylinder after the exhaust-port is closed will escape so slowly as to serve as a cushion for the piston and prevent it pounding the cylinder-head.

What I claim as new, and desire to secure by Letters Patent of the United States, is—

1. In a steam-engine, the combination of a series of cylinders arranged in a circle, with their axes parallel, or nearly so, a piston arranged to work in each of said cylinders, a shaft mounted in bearings, with its axis equidistant from each of said cylinders and having a portion thereof at one end oblique to its main body, a hemispherical crank sleeve or casting mounted upon the oblique portion of said shaft, with its flat face toward said cylinders, a hemispherical socket or abutment fitted to the spherical side of said crank sleeve or casting to receive the thrust of the shaft and the pistons, and a socketed shoe applied to the end of each of said pistons and constructed and arranged to bear against the flat side of said crank-sleeve and to be moved in any direction about its connection with its piston.

2. The combination of a series of cylinders arranged in a circle and all formed in a single casting having the conical surfaces *h h'*, a shaft arranged with its axis equidistant from each of said cylinders, and having a portion

of its length oblique to its main body, a hemispherical crank sleeve or casting mounted upon said oblique portion of the shaft with its flat side in contact with said conical surfaces, a casing inclosing said hemisphere and having its interior in the form of a section of a sphere fitting closely the convex surface of said hemispherical crank-sleeve casting, a piston fitted to each of said cylinders, a shoe fitted to each of said pistons by a ball-and-socket joint and having a flat side to bear against the flat side of said hemispherical crank sleeve or casting.

3. The combination of the casting *A*, having formed therein a series of cylinders arranged in a circle, a piston arranged in each of said cylinders, the shaft *B*, having the oblique portion *B'* and crank-pin *f*, the hemispherical crank-sleeve *E*, the casting *F*, having its inner surface in the form of a section of a sphere, the stud *H*, set in the casting *G*, and having its inner or headed end concaved to fit the convex surface of said hemispherical crank-sleeve *E*, the counter-balance *I*, and the socketed shoes *d d*, all constructed, arranged, and adapted to operate substantially as described.

4. In a steam-engine, the combination of a series of cylinders arranged in a circle, each having one open end, a casing inclosing the open ends of all of said cylinders and having formed therein a hemispherical chamber or bearing-surface, an oscillating hemisphere fitted to said casing and adapted to be moved in any direction therein about the center of its flat side or equatorial plane, and a piston fitted to each of said cylinders and arranged to act against the flat side of said hemisphere to move it without being attached thereto.

5. In a steam-engine, the combination of a cylinder-casting having formed therein a series of cylinders arranged in a circle and all open at one end, and provided between said open ends with a conical bearing-surface, a casing inclosing the open ends of said cylinders and said conical bearing-surface and having its inner surface in the form of a segment of a hollow hemisphere, an oscillating hemisphere fitted to said casing with its flat side in contact with said conical bearing-surface, a piston in each of said cylinders, and a socketed shoe mounted upon each of said pistons and provided with a flat side arranged to bear against the flat side of said hemisphere.

6. In a steam-engine, the combination of a series of cylinders arranged in a circle, and each provided with a steam-port in its end and an exhaust-port in its side, a piston fitted to reciprocate in each of said cylinders, a ring-valve arranged to open and close said steam-ports and control the admission of steam to said cylinders by its outer or peripheral edge and permit the escape of steam through the same ports past its inner edge, and an adjustable compression-ring secured to said valve

and adapted to throttle the escaping steam and cause it to serve as a cushion for the piston.

7. The valve *J*, provided with the threaded annular rectangular groove *n* and the series of holes *o*, in combination with the threaded ring *m* and the locking-pin *p*, all constructed and arranged substantially as described.

In testimony whereof I have signed my name to this specification, in the presence of two subscribing witnesses, on this 28th day of March, A. D. 1887.

WILLIAM ESTY.
